UNITED STATES PATENT OFFICE.

HERBERT J. TILLY, OF SWAMPSOFT, MASSACHUSETTS, ASSIGNOR TO FORBES LITHOGRAPH MANUFACTURING COMPANY, OF BOSTON, MASSACHUSETTS, A CORPORATION OF MASSACHUSETTS.

DISPLAY STAND.

Application filed September 23, 1922. Serial No. 590,006.

This invention relates to display stands, that is, to those structures, usually formed of cardboard or the like, which may be erected on a counter or in a window for the display of advertising matter and which usually provide for the simultaneous support of articles to be sold.

My invention will be clearly understood by reference to the following description of the illustrative embodiment thereof shown by way of example in the accompanying drawings, wherein:

Fig. 1 is a front elevation of the blank from which the stand is made;

Fig. 2 is a front elevation of the stand in erected position;

Fig. 3 is a section on the line 3—3 of Fig. 2 on a larger scale; and

Fig. 4 is a section of the parts shown in Fig. 3 in collapsed or folded position.

Referring to the drawings, the display stand here shown as an example of the invention may be constructed from a blank comprising a single sheet of cardboard which, as shown in Fig. 1, may have a portion B which constitutes the back of the stand when it is erected, as shown in Fig. 2, and is adapted to receive advertising matter or an attractive picture. Cut from the sheet below the portion B I show a tongue T which defines around the sides thereof a marginal portion M.

The marginal portion M of the blank is herein bent to form a prismatic base or support which, because the tongue is cut out from the same, is provided with an opening in its top, and preferably also as herein in its front, face, whereby it may receive articles to be displayed or sold, such as the small cartons C as indicated in Fig. 2. As the prismatic support formed by the portion M of the blank is similar in appearance to a stair or step it will be convenient in describing the same to use the nomenclature commonly applied to such a structure. Herein the base portion is formed by bending the marginal portion M along the lines 5 substantially at the base of the tongue T to form (see Fig. 3) lateral treads 7 and then along the lines 9 to form the risers 11. The end of the blank may then be bent along the line 13 rearwardly to form a base 15 and it may further be provided with a bent up integral

tab 17 adapted, as shown in Fig. 3, to lie in the plane of the back portion B and the parts are preferably held in position by securing the tab 17 to the flange 19 of an easel support of any known or suitable form which is attached to the back of the section B and is adapted to be unfolded, as shown in Fig. 3, and held in extended position by the foldable strut or brace 21 as shown to support the display stand in its erected position. Preferably, as clearly shown in Fig. 1, the folding line 13 is below the end of the tongue T so that the two risers 11 are connected along their lower portion (see Fig. 2) by a connecting rail 23 and, as shown in Fig. 2, cartons C or other articles may be placed in the receptacle thus defined behind the rail 23 and between the two ends formed by the steps which embody the treads 7 and risers 11.

In the preferred form of my invention herein shown the tongue T may also be formed into a prismatic support which herein is shown housed within that formed by the marginal portion M and located at the lower rear corner thereof and this may provide means for supporting another series of cartons C at a different elevation from those which rest on the base portion 15 so that the former will be displayed for view projecting above the tops of the latter. For this purpose the tongue T may be bent differentially to the marginal portion M to form a supporting surface, preferably of prismatic form, and herein it is first bent along the line 25 located in a different position on the blank to the lines 5 to provide a tread portion 27. Herein the line 25 is below the lines 5 and the tread portion 27 will similarly be disposed below the tread portion 7, the top of the tongue forming a rear riser 29. The tongue is further bent on the line 31 to form a front riser 33 and may be provided with a folded-over base 35 which may be secured to the base 15, as shown in Fig. 2. In the preferred form of the invention a row of articles may be housed in front of the riser 33 and behind the rail 23 to be supported on the base 15 and another row of articles may be arranged behind them for display above their tops on the tread 27. Obviously, however, the tongue T may be utilized primarily to define the foldable marginal portion M

which forms a prismatic base having an open top or an open top and side adapted to receive articles for display or the tongue T may be folded differentially from said marginal portion to provide an article support which is framed and sustained by a structure formed from the folded marginal portion not in itself primarily utilized for the support of articles.

10 I have in this description referred to folding the tongue T and the marginal portion M along various lines referred to but it will be understood that this folding refers primarily to an initial folding in the course of manufacture and that these lines in the finished article constitute in effect permanent hinge joints. The structure may be erected or expanded in the position shown in Figs. 2 and 3 and held erected by the easel support or other suitable means and after collapsing the easel the entire stand may be collapsed by a relative hinging of the parts along the lines indicated and the whole display stand will fold flat in the manner shown in Fig. 4 in a form convenient for shipment or storage. The manner in which the parts are collapsed may be gathered from Fig. 3 by imagining the parts at the left of the line 13 in Fig. 3 to swing upwardly and clockwise around that line as a center to the position shown in Fig. 4.

I have described in detail the particular form of my invention shown by way of example in the accompanying drawings but it will be understood that this full description has been in view of clearness and has not been for the purpose of defining the scope of the invention. Obviously the structure might be widely varied and the features of invention exemplified by the particular embodiment shown which I desire to secure by Letters Patent I shall express in the following claims.

I claim:

- 45 1. A display stand comprising a sheet having a tongue formed therefrom connected thereto along one side and defining margins about said tongue at the other sides, which margins form sides of a prismatic structure and said tongue forming sides of a prismatic structure housed at the lower rear portion of the first.
- 50 2. A display stand comprising a sheet having a tongue formed therefrom connected thereto along one side and defining margins

about said tongue at the other sides, which margins form sides of a prismatic structure, and said tongue forming sides of a prismatic structure, said structures being of different dimensions in cross section but having substantially coplanar bases.

3. A display stand comprising a sheet having a tongue formed therefrom connected thereto along one side and defining margins about said tongue at the other sides, which margins form sides of a prismatic structure open between the end at the top and for a part of the height of its forward face and said tongue forming sides of a second prismatic structure exposed through the open part of the first, the bases of said structures being substantially coplanar.

4. A display stand comprising a sheet having an upper portion providing a display surface and below the same having a marginal portion comprising lateral and lower parts, which parts form sides of a foldable prismatic structure, the cross section of which is a parallelogram, said structure having a base extending, when the parts are erected, to the plane of the upper portion, the rear edge of the base being connected to said upper portion.

5. A display stand as defined in claim 4 wherein said upper portion has also below the same a central portion received inwardly of said marginal portion, which central portion forms sides of a second foldable prismatic structure of different cross section, the prisms having a base and side in common whereby both structures may fold together.

6. A display stand comprising two foldable parallelopipeds of different cross section having a common edge and folding along parallel edges, the larger being interrupted and open adjacent one edge between its ends to expose the inner.

7. A display stand having a base presenting two foldable parallelopipeds of different sizes having a lower rear edge in common and comprising a single sheet having a central portion which forms the top and front of one such parallelopiped and a portion marginal of said central portion which provides the top and front of the other.

In testimony whereof, I have signed my name to this specification.

HERBERT J. TILLY.
